Primary Examiner — April Rivas*Assistant Examiner* — Jillian Mazzola(74) Attorney, Agent, or Firm — Vladimir Postnikov(57) CLAIM

The ornamental design for a jewellery casket, as shown and described.

DESCRIPTION

FIG. 1 is a front elevation view of a jewellery casket showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof; and,

FIG. 9 is a perspective view of the jewellery casket in an open position.

The broken lines depict portions of the jewellery casket that form no part of the claimed design.

1 Claim, 9 Drawing Sheets(56)
